FLUID DISPENSER

Michael Mazzanobile, New York, N. Y.

Application June 1, 1938, Serial No. 211,167

2 Claims. (Cl. 225—26)

This invention relates to fluid dispensers, and aims to provide a device by means of which a mixture of two fluids commonly used as a syrup and soda water, or a liquor and soda water, may be selectively or simultaneously passed into a container, such as a glass, the quantity of the syrup or liquor thus dispensed being predetermined by the setting of a regulating means forming part of the device.

The above and other objects will become apparent in the description below in which characters of reference refer to like-named parts in the accompanying drawings.

Referring briefly to the drawings, Figure 1 is a side elevational view of the device.

Figure 2 is a bottom plan view of the same.

Figure 3 is a cross-sectional view taken on the line 3—3 of Figure 1.

Figure 4 is an erected cross-sectional view taken on the line 4—4 of Figure 2, showing the liquor regulating means in one position.

Figure 5 is a fragmentary cross-sectional view of the liquor chamber, of Figure 4, showing the liquor regulating means in another position.

Figure 6 is a fragmentary side elevational view of the device, partly in section, and showing the liquor regulating means in a third position.

Referring in detail to the drawings, the numeral 10 indicates a transparent cylinder having screw caps 11 and 12 at the top and bottom, respectively, these members enclosing the syrup or liquor chamber 13. The caps 11 and 12 have axially aligned threaded openings 14 and 15, respectively, therethrough. A tube 16, threaded on both its exterior and interior surfaces, projects threadably downward through the opening 14 and has a knurled ring 17 on its upper end. A tube 18, threaded on its exterior surface only, projects upward through the opening 15, and has a knurled ring 19 on its lower end. A packing nut 12a surrounding the tube 18 is turned up against the cap 12. Within the upper tube 16, a thinner tube 20, with threads on its outer surface only, is in threadable engagement with the inner threads of the tube 16. A tube 21, having its interior surface smooth throughout and its exterior surface smooth except for threads 22 on the lower end of its exterior surface, is slidably mounted within the tube 18. A smooth-surfaced tube 23, having a collar 22 at a point nearer its upper end, is slidably mounted within the tubes 20 and 21, with the collar 24 positioned between the adjacent extremities of the tubes 20 and 21 and serving as a limit stop in the approach of the latter tubes toward each other. It is to be noted that the tube 21 has a flange 25 on its upper end, which overlaps the upper end of the tube 18. Just above the collar 24, a transverse opening 26 passes diametrically through the tube 23, and a similar opening 27 is provided just below the

collar. The threaded end 22 of the tube 21 projects through and threadably engages an opening in a horizontal brace or support 28. A knurled nut 29, having a smooth opening therethrough, through which the tube 23 projects slidably, is screwed on the end 22 of the tube 21, and retains the brace 28 between the ring 19 of the tube 18 and itself. Near its lower extremity the tube 23 has a shoulder 30 from which the reduced stem 31 of this tube projects through an opening 32 in a member 33 described below. The lower extremity of the stem 31 is threaded, and a knurled nut 34 limits the member 33 to movement between the latter nut and the shoulder 30. A coiled spring 35 normally urges the member 33 away from the nut 29.

The support 28 has a second threaded opening therethrough, through which a threaded tit 36 projects downward, this tit forming part of a cylindrical housing 37 having its upper interior edge screw threaded, and being further provided with an internal shoulder 38. A tube or stem 39 is slidably mounted in the tit 36 and the head 40 on its upper extremity is adapted to rest on the shoulder 38. A knurled nut 41 surrounds the projecting end of the tit 36, and the stem 39 projects slidably through a smooth central opening therein. The construction of the lower end of the stem 39 is similar to that of the lower end of the tube 23, the shoulder being shown at 30a, the reduced portion at 42, and the nut on the end at 44, the opening in the member 33 through which the portion 42 projects being shown at 43, and the spring at 35a.

A cylinder 45 is provided with a threaded tit 46 which registers in the threaded upper end of the housing 37. The upper end of the cylinder 45 also has a threaded tit 48 which is engaged by a knurled nut 49 having a smooth opening through its center. The cylinder 45 has a smooth axial channel in which a tube 50 is slideable. The upper end of the tube 50 is widened to form a neck 51 having external threads on its upper extremity. The upper peripheral surface of the cylinder 45 is also knurled, as shown at 53. The stem 39 has a transverse opening 54 just below its head 40, extending diametrically through the stem.

The device is held in upright position by any suitable means, not shown. A hose or pipe, not shown, leading from a source of liquor, syrup or other fluid supply, is connected to the top of the tube 20. A second hose or pipe, not shown, leading from a tank containing carbonated or soda water, is connected to the top 52 of the tube 50. The member 33 serves as a handle or lever which is operated by pushing either end thereof upward, or the entire member upward at once. It is obvious that when the right hand end (Figure 4) is pushed upward a sufficient dis-

tance to raise the opening 54 of the stem 39 clear of the shoulder 38, the soda water will pass from the housing 37 through the stem 39 and out through the lower end of the stem.

5 In Figure 5, both openings 26 and 27 are shown closed; hence, assuming that the flow of syrup into the top of the tube 20 is on, the same will be checked at the opening 26 by the lower periphery of the tube 16 and the collar 24. This is 10 the condition in which the device may be kept when not in use, as, for instance, over night, and is attained by screwing down the nut 17 (since the tube 20 is permanently attached to the syrup conduit or pipe, it will not be rotatable thereafter). To place the device into condition 15 for use as a dispenser, the nut 17 is screwed upward until the lower edge of the tube 16 rises clear of the upper opening 26 in the tube 23, as shown, in Figures 1 and 4, which also show the lower opening 27 closed by the upper end of the tube 21. When the upper opening 26 is thus 20 freed, syrup will be free to pour down through said opening and into the chamber 13. To permit the syrup to flow into the chamber, the left 25 hand end of the lever 33 is pushed upward (and held in that position) a sufficient distance to partly unseal both openings 26 and 27. When the lever in the chamber rises above the lowest point of the opening 27, it will flow down the tube 23 below the collar 24, and as soon as it 30 begins to flow out at the bottom of the tube 23, the lever 33 is released, the spring 35 then causing it to draw down the tube 23 and seal the opening 27 while fully unsealing the opening 26. 35 Syrup will continue to pass into the chamber through the opening 26 until the air at the top of the chamber will have been compressed to a point at which its pressure equals that of the incoming syrup, and then the incoming flow will 40 stop, at a level somewhat above the uppermost point of the opening 26. The flowing syrup may be given a sufficient pressure by a force pump or by gravity.

In use, a glass is held under the device with 45 its rim surrounding both nuts 34 and 44. The left hand end of the lever 33 is pushed up, thus unsealing the opening 27. The escape of the syrup through the opening 27 will be enhanced at first by the pressure of the trapped air, mentioned above. The lever is held in that position until the level of the syrup in the chamber has fallen to the level of the lowest point of the opening 27, at which time the outward flow will 50 stop. The pressure against that side of the lever 55 is then released and the right hand side of the lever is then pushed up thus causing soda water to flow into the glass, as previously described, the latter flow being stopped when the desired amount has been dispensed, by simply releasing 60 the lever. If both ends of the lever are moved together, the limited quantity of syrup, above mentioned, will flow into the glass, and the soda water will flow simultaneously. If desired, the lever could be operated by applying the rim of 65 the glass thereagainst.

The amount of syrup represented by the volume of the disc between the topmost level (where the air pressure balances the incoming syrup pressure) and the bottommost level (the lowermost 70 level of the opening 27) is the portion dispensed each time the glass is thus applied to the left

hand end of the lever. When the left hand end of the lever has been permitted to fall, as just mentioned, with the consequent sealing of the opening 27 and unsealing of the opening 26, the incoming syrup will again flow into the chamber 5 to the same level mentioned above, at which the air pressure balances the syrup pressure. Thus, each portion of syrup thus dispensed will be of the same volume. If it is desired to reduce the volume of each portion, the nut 17 may be 10 screwed down, so as to reduce the area of the opening 26 when the tube 23 is in raised position by bringing the lower edge of the tube 20 partway down across the said opening.

It is obvious that a combination dispenser of 15 both syrup and soda water, or any other desired combination of fluids, has been provided, possessing the many useful and practical features which need not be mentioned specifically.

Obviously, modifications in form and structure 20 may be made without departing from the spirit and scope of the invention.

I claim:

1. A fluid dispenser comprising a housing enclosing a chamber and having an inlet pipe at 25 the top and an outlet pipe at the bottom, said pipes projecting axially into said chamber and having their ends within the chamber mutually spaced apart, a tube projecting upward through said outlet pipe into the chamber and into said 30 inlet pipe, said tube being slideable in said pipes and having a collar thereon projecting into the space between said adjacent ends of said pipes, said tube having a transverse opening therethrough above said collars and a similar opening 35 below said collar, said upper opening being sealed by the lower end of said inlet pipe and said lower opening being free when said tube is in elevated position, said lower opening being sealed by the upper end of said outlet pipe and 40 said upper opening being free when said pipe is in lowered position, means for normally urging said tube into said latter position, and a lever attached to said tube adapted to be raised to elevate said tube.

2. A fluid dispenser comprising a housing enclosing a chamber and having an outlet pipe at the bottom and an inlet pipe at the top, said pipes projecting axially into said chamber and having their ends within the chamber mutually spaced apart, a tube projecting upward through said outlet pipe into the chamber and into said inlet pipe, said tube being slideable in said pipes and having a collar thereon projecting into the space between said adjacent ends of said pipes, said tube having a transverse opening therethrough above said collar and a similar opening below 50 said collar, said upper opening being sealed by the lower end of said inlet pipe and said lower opening being free when said tube is in elevated 55 position, said lower opening being sealed by the upper end of said outlet pipe and said upper opening being free when said pipe is in lowered position, means for normally urging said tube into said latter position, and a lever attached to said tube adapted to be raised to elevate said tube, and means for moving said pipes toward or away from each other to vary the distance between said adjacent ends of said pipe.
